UNDERGARMENT FOR LADIES OR
CHILDREN

Eleanor Donaldson and Jane Gibney, Minneapolis, Minn.; said Gibney assignor to Munsingwear, Inc., Minneapolis, Minn., a corporation of Delaware

Application February 27, 1946, Serial No. 650,542

3 Claims. (Cl. 2—224)

1

This invention relates to an undergarment for women and girls and particularly to such a garment commonly now known as panties. In such a garment it is desirable that the same be made of goods which has considerable stretch or elasticity and it is highly important that the crotch piece be properly formed and properly disposed so that the garment functions to the best advantage and gives the greatest comfort.

It is an object of this invention to provide a garment for women and girls, such as panties, the same having a body portion, leg portions and a crotch portion, together with a band at its top adapted to extend around the waist of the wearer, which band may be elastic, a rear piece extending downwardly from said band and from one side of said garment to the other said rear piece being made of material having the stretch thereof downwardly, leg portions to which said rear piece extends and to which it is secured, a front piece extending downwardly from said band and connected to said rear piece by seams extending vertically at the sides of said garment, said front piece extending to and secured to said leg portions, and a crotch piece extending between said front and rear pieces and secured thereto and extending upwardly from said leg portions, said crotch piece being disposed wholly between said leg portions and preferably being made of material having the stretch thereof laterally of said garment.

It is another object of the invention to provide such a garment as set forth in the preceding paragraph in which said crotch piece has its front side much closer to said band than its rear side.

It is a further object of the invention to provide a garment for women and girls, such as panties, the same having a band at its top adapted to extend around the waist of the wearer, which band may be elastic, a rear piece extending downwardly from said band and from one side of said garment to the other, said rear piece being made of material having the stretch thereof downwardly, leg portions to which said rear piece extends and to which it is secured, a front piece extending downwardly from said band and connected to said rear piece by seams extending vertically at the sides of said garment, said front piece extending to and secured to said leg portions, and a crotch piece extending between said front and rear pieces and between said leg portions, said crotch piece extending upwardly from said leg portions to the crotch or center of the crotch piece, said crotch piece being of somewhat greater dimension between said leg portions than between said front and rear pieces and preferably having outer convexly curved edges, the front one of which is much closer to said band than the rear one.

These and other objects and advantages of the

2

invention will be fully set forth in the following description made in connection with the accompanying drawings in which like reference characters refer to similar parts throughout the several views and in which:

5 Fig. 1 is a view in front elevation of the garment as it will appear upon the wearer;

Fig. 2 is a partial view in vertical section taken on line 2—2 of Fig. 1, as indicated by the arrows;

Fig. 3 is a view in front elevation of the garment laid out in somewhat flat position;

Fig. 4 is a view similar to Fig. 3 but being in rear elevation of said garment; and

Fig. 5 is a bottom plan view of said garment.

Referring to said drawings, a garment is shown 10 comprising a waist band 10 adapted to encircle the waist of the wearer, and while this band could be variously formed, in the embodiment of the invention illustrated it is shown as of narrow width and the same will preferably be formed 15 of elastic material so that the band can be stretched and the garment drawn over the hips of the wearer. A rear piece 11 extends downwardly from band 10 and from one side of the garment to the other, said piece extending downwardly to short leg portions 12. Leg portions 12 could be varied in length and form but in the embodiment of the invention illustrated they are shown as quite short and in practice these have 20 been made of material which is somewhat elastic and circumferentially expansible or stretchable.

The rear piece 11 is preferably made of material which has the stretch thereof vertically. Rear piece 11 will be secured to the upper edges of leg portions 12 by a suitable stitching 13. A front piece 14 is provided extending from band 10 downwardly to leg portions 12 to which it is secured by suitable stitching 15 and rear piece 11 and front piece 14 are secured along the sides of the garment by suitable stitching or a seam 16. In 25 order to provide for the stretching of band 10, front and rear pieces 14 and 11 are gathered somewhat at the band 10, as indicated at 14a and 11a. Front piece 14 is preferably made of material 30 having its stretch horizontally. A crotch piece 18 is provided, the same having a rear edge convexly curved at its outer side and secured to rear piece 11 by suitable stitching 19. Said crotch piece 18 has a front edge which is also convexly 35 curved at its outer side and is secured to front piece 14 by suitable stitching 20. Crotch piece 18 extends between the leg portions 12 and is secured thereto by suitable stitching 21. Crotch piece 18 extends upwardly from the leg portions 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

extending from the center of the crotch down-

ward to the bottom of portions 12. The median line of the crotch piece in a direction laterally thereof or extending between the leg portions is disposed forwardly of the line extending through the centers of the leg portions 12, as shown in Fig. 5, and the front edge of the crotch piece is thus much closer to the band 10 than is the rear edge of the crotch piece. Preferably the crotch piece 18 will be made of material having the stretch thereof laterally or toward and from the leg portions.

The above described structure forms a garment having desirable functions and one which is very comfortable. It will be noted that the crotch piece 18 forms very little of the rear of the garment. When the wearer sits therefore, the stretch of the garment can take place from the band 10 almost to the crotch. The wearer can thus really sit into the stretchable part of the garment and this results in great comfort and no binding. At the same time any stretch that must take place laterally in the sitting position is accommodated by the lateral stretch of the front portion 14. The fact that the crotch piece is disposed forwardly also adds to the comfort of the garment as it tends to prevent the garment entering in or binding in the crease between the rear part of the legs. In a garment for women and girls it is not desirable to have a crotch piece which extends in a more horizontal position and further upwardly in the rear. By having the crotch piece 18 extend upwardly from the leg portions to the crotch, as shown, a very smooth fitting and comfortable garment is provided for one of the feminine sex. The stretch of the crotch piece 18 provides ample freedom for any movement of the legs and the elasticity of the crotch piece insures that the same will have a smooth fit at all times. In a lady's garment the crotch piece can also be much smaller than in a garment for men. It has heretofore been proposed to have material that will stretch upwardly and downwardly in the rear of the garment and laterally in the front of the garment and crotch piece but this alone will not give the desired comfort and effect without the crotch piece being properly formed and disposed.

It is pointed out that the garment of this invention has a body portion, leg portions and a crotch portion. These terms are used generally and the crotch portion denotes the portion of a garment that covers the crotch of the wearer or the part of the body between the legs. The term "crotch portion" as used in the specification and claims is not the same as the term "crotch piece." The crotch piece refers to the piece designated 18 on the drawing and this includes not only the part covering the crotch of the wearer but also the parts at each side thereof which extend to the leg portions 12 and are disposed along the inner sides of the legs of the wearer.

From the above description it will be seen that we have provided a garment for women and girls having many desirable functions and one which gives a very smooth fit and gives great comfort. It will be noted that front and rear portions 14 and 11 are continuous between the seams 15. The form, relative size and location of the crotch piece in combination with the direction of stretch of the portions result in a garment having a snug fit and the desired freedom of movement. The garment has been amply demonstrated in actual practice, found to be very successful and efficient and the same is being commercially made.

It will of course be understood that various changes may be made in the form, details, arrangement and proportions of the parts, without departing from the scope of applicants' invention, which generally stated, consists in a garment capable of carrying out the objects above set forth, in the parts and combinations of parts disclosed and defined in the appended claims.

What is claimed is:

1. An underwear garment for women or girls and comprising body and leg portions and also a crotch portion having in combination, a band at the top of said garment adapted to encircle the waist, a rear piece extending downwardly from said band to a short distance above said crotch portion of the garment, said rear piece being made of material stretchable vertically, a front piece extending downwardly from said band having its bottom edge spaced above said crotch portion a considerably greater distance than said distance, said front piece being made of material stretchable transversely and being secured at its sides to the sides of said rear piece and a crotch piece secured at its rear to the bottom of said rear piece and at its front to the bottom of said front piece, said crotch piece thus being disposed principally at the front of said garment.
2. The structure set forth in claim 1, said crotch piece being of comparatively narrow construction forwardly and rearwardly of said garment, the same extending to said leg portions and being disposed substantially altogether in the zone between the legs of the wearer.
3. An underwear garment for women or girls comprising body and leg portions and a crotch portion having in combination, a band at the top of said garment adapted to encircle the waist, a rear piece extending downwardly from said band to a short distance above said crotch portion, said rear piece comprising an unbroken piece of material stretchable vertically but having little stretch transversely, a front piece extending downwardly from said band having its bottom spaced a considerably greater distance than said distance above said crotch portion, said front piece being made of an unbroken piece of material which is stretchable transversely but has little stretch vertically and being secured at its sides to the sides of said rear piece, and a crotch piece secured at its rear to the bottom of said rear piece and at its front to the bottom of said front piece, said crotch piece being thus disposed principally at the front of the garment and being made of material which is stretchable transversely of the garment, said crotch piece extending to said leg portions.
